UNITED STATES PATENT OFFICE.

FELIX ROGOWSKI, OF CHICAGO, ILLINOIS.

STREET-CLEANING MACHINE.

No. 895,201.

Specification of Letters Patent.

Patented Aug. 4, 1908.

Application filed February 24, 1908. Serial No. 417,444.

To all whom it may concern:

Be it known that I, FELIX ROGOWSKI, a citizen of the United States, and a resident of Chicago, in the county of Cook and State of Illinois, have invented certain new and useful Improvements in Street-Cleaning Machines, of which the following, when taken in connection with the drawings accompanying and forming a part hereof, is a full and complete description, sufficient to enable those skilled in the art to which it pertains to understand, make, and use the same.

This invention relates to a street cleaning machine propelled by an engine mounted thereon.

The object of this invention is to obtain a street cleaning machine simple in construction, not liable to get out of order, and durable; by means of which a street, alley or boulevard may be swept and the sweepings obtained will be loaded into a garbage or other wagon attached thereto.

A further object of the invention is to obtain a street cleaning machine of the character named which can move or be moved over a street, alley or boulevard with the sweeping or cleaning devices thereof in an inoperative position.

A further object is to obtain a machine of the kind named to which an ordinary garbage wagon can be removably attached, so that in the use of the machine a number of wagons can be successively attached to and detached from such machine.

In the drawings referred to Figure 1 is a side elevation of a street cleaning machine embodying my inventions; such figure also showing in side elevation the front part of a garbage wagon attached thereto, with the tongue of such garbage wagon removed. Fig. 2 is a top plan view of a street cleaning machine embodying this invention, and of the forward part of a garbage wagon attached thereto. Fig. 3 is a rear elevation of a street cleaning machine embodying this invention, with the elevator of the device omitted therefrom. Fig. 4 is a sectional view of a shaft and an elevation of the attachments thereto by means of which it is raised from an operative into an inoperative position. Fig. 5 is a top plan view of position of shafts and journal bearings forming elements in a device embodying this invention.

A reference letter applied to designate a given part is used to indicate such part

throughout the several figures of the drawings wherever the same appear.

A is the body of a street cleaning machine; B, B' are the wheels thereof; and b the rear axle. Wheels B, B', are shown secured to the axle b and driven by the rotation of such axle.

C is an engine mounted on body A.

D, (Fig. 3) is an ordinary differential gear used with road propelled devices.

E is an ordinary sprocket chain.

F is what is known in the art as a transmission gear, and is mounted on the crank shaft of the engine C. Sprocket chain E forms the flexible connection between the transmission gear of the engine C and the differential gear of the device, and is actuated by control of the transmission gear in the ordinary way.

G is a spring interposed between axle b and body A.

H is a garbage wagon removably attached to the street cleaning machine embodying this invention by connecting bars h, h, such bars being provided with holes through which the bolts h', h' pass.

I, I' are street sweeping brushes provided with shafts i, i, respectively, and such shafts are rotatably mounted in journal bearings j, j'.

I" is a non-rotatable brush which is adjustably attached to the body A, as by chains J, J' and pivoted arm or connection J".

j" is the bolt forming the pivot of arm J".

Journal bearings j, j, are respectively attached to the lower ends of the several connections K, K and such arms are pivotally attached to body A by bolts k and forgings or castings k'. Forgings or castings k' are attached to the body A by bolts or lag screws k". Bearings j, j are also attached to body A by chains k', which extend over idlers K", see Fig. 3, and to shaft U, (or hub u on such shaft) hereinafter more fully described.

Journal bearings j', j' are, respectively, in the forward ends of bent irons L, L; and such bent irons are supported at their rear ends on shaft M, by journal bearings l, l. The forward ends of the bent irons L, L, are respectively attached to the body A by chains o, o, which extend over idlers K", see Fig. 3, and to the shaft U.

M is a shaft rotatably mounted in journal bearings N, N. Bearings N, N, are respectively attached to the body A by arms or

connections n , n , (forming tie rods), and chains O' . Tie rods n , n , are pivoted to the body A by bolts n' , n' . Chains O' , O' are attached to the shaft U.

5. P, P' are beveled gear wheels rigidly secured to shaft M, to turn therewith; and Q, Q' are sprocket wheels rigidly attached to such shaft M.

p , p' are beveled gear wheels on the ends of 10 the brushes I, I', respectively, and are arranged to intermesh with the beveled gear wheels P, P'.

R is a sprocket wheel loosely mounted on axle b, and r is a clutch arranged to be 15 thrown into and out of gear with the wheel R, to turn such wheel R with the shaft when in engagement therewith.

q is a sprocket chain on sprocket wheels 20 Q and R. When clutch r is in engagement with wheel R the shaft M is turned by the engine C, by means of sprocket chain q, when the device is in operation. The position of the clutch r is controlled by means of bell crank r', connecting rod r', and lever R', 25 (Figs. 1 and 2).

S is a clutch to engine C and transmission gear F.

T is an apron and T' is a runway provided with an elevator t.

30 t' is a sprocket wheel at the upper end of runway T', over which the elevator t extends or runs. Elevator t also extends over the sprocket wheel Q', on shaft M, so that revolution of such sprocket wheel Q', actuates the 35 elevator. Runway T' is suspended from body A by links t'', t''. The upper pair of links t'' are pivotally attached, by bolt T'' to the sides of runway T', and by link T''' to bar t'''; and such bar t''' is rigidly attached to 40 frame A. The lower pair of links t'' are hung at their upper ends on shaft b and at their lower ends are pivotally secured to the side of the runway T' by bolts T''.

The several chains J, K', O and O' are used 45 to raise the several brushes I, I' and I'' into an inoperative position; and also to raise the apron T and runway T'. Such chains are attached to the shafts U, U, or to the chain wheels u, u, which are rigidly secured to such 50 shafts; and the shafts are respectively secured to the body A by being rotatively mounted in the journal bearings provided therefor, (V, V).

U' is a hand wheel rigidly secured to a 55 shaft journalized in bearings V', V', and U'' is a sprocket wheel rigidly attached to such shaft.

u' is a flexible connection, as a sprocket 60 wheel chain, over sprocket wheel U'' and sprocket wheel u''. Sprocket wheel u'' is rigidly attached to shaft U. The forward end of apron T is supported by connections U''', which are hung on the shaft M and attached to the apron by bolts u'''. The rear end of such apron is attached to the sides of 65 runway T' by bolts u'''. Rotation of hand

wheel U' turns shafts U, U, and winds the several chains on the shaft, or on the chain wheels which are mounted on such shaft, and elevates the several journal bearings attached thereto, together with the 70 apron T and the lower end of the runway T'.

When the device is to be moved to the street, alley or boulevard where it is to be used for cleaning the street the several brushes, the apron and the lower end of the 75 runway are elevated by winding the chains attached to the shafts U around such shafts. When used for cleaning the street the shafts U, U, are turned to allow the brushes to rest on the street, and the clutch r is thrown into gear to turn the wheel R and shaft M. When a wagon H is filled it is detached and another wagon is attached to the device in place thereof.

Having thus described my invention, the 85 construction of a machine embodying the same, and the operation thereof, what I claim as new and desire to secure by Letters Patent is,—

1. In a street cleaning machine, the combination of a wagon body, wheels and axles thereto on which the body is mounted, the wheels on the rear axle constituting the driving wheels of the machine, an engine mounted on the wagon body, a connection between 90 such engine and the driving wheels, means to throw such connection into and out of operative relation with the driving wheels, a rotatable shaft, gear and sprocket wheels on the shaft, a connection between the shaft and the 95 engine, means to throw such connection into and out of operative relation with the shaft, rotatable brushes arranged diagonally to the axles of the machine, journal bearings for such brushes, gear wheels on the rotatable 100 brushes arranged to intermesh with the gear wheels on the rotatable shaft so that one of such brushes will rotate in one direction and the other in the opposite direction, an apron, a runway extending backward and upward 105 from the rear end of the apron, an elevator in the runway, such elevator extending over the sprocket wheels on the rotatable shaft, shafts rotatably mounted on the wagon body, means to turn the shafts, chains attached to 110 the journal bearings of the brushes and of the rotatable shaft and to the shafts on the wagon body, respectively.

2. In a street cleaning machine, the combination of a wagon body, wheels and axles 115 thereto on which the body is mounted, the wheels on the rear axles constituting the driving wheels of the machine, an engine mounted on the wagon body, a connection between the engine and the driving wheels, 120 means to throw such connection into and out of operative relation with the driving wheels, a rotatable shaft, journal bearings for such 125 shaft, a connection attached to the respective journal bearings and pivotally attached to 130

the wagon body, gear and sprocket wheels on the shaft, a connection between the shaft and the engine, means to throw such connection into and out of operative relation with the 5 driving shaft, brushes respectively provided with shafts, journal bearings for the brush shafts, a connection attached to the journal bearings at the forward ends of the brush shafts and attached to the wagon body, the 10 journal bearings of the brush shafts at the rear ends of such brushes comprising a bar journaled at its rear end on the rotatable shaft, gear wheels on the rotatable brushes arranged to intermesh with the gear wheels on 15 the rotatable shaft to rotate one of the brushes in one direction and the other in the opposite direction, an apron, a runway from the rear of the apron, an elevator in the runway, such elevator extending over the 20 sprocket wheels on the shaft, and means to raise the brushes from the ground; substantially as described.

3. In a street cleaning machine, the combination of a wagon body, wheels and axles 25 thereto on which the wagon body is mounted, the rear wheels attached to the axle thereof to rotate therewith, a connection between the engine and the rear axle, means to throw such connection into inoperative position, a 30 rotatable shaft, journal bearings to such shaft, a connection between each of such journal bearings and the wagon body, each of such connections pivotally attached to the wagon body, and a chain attached to such 35 journal bearings, rotatable shafts mounted on the wagon body, such chains attached to such shafts, means to turn the shafts on the wagon body, rotatable brushes, gear wheels on the brushes and on the first named rotatable shaft arranged to intermesh and to 40 turn the brushes in opposite directions, journal bearings to the brushes, chains attached to such journal bearings and to the rotatable shafts on the wagon body, the bearings at the 45 rear ends of the rotatable brushes comprising a bar journaled on the first named rotatable shaft, an apron, an elevator runway, and an elevator in the runway, such apron extending over the sprocket wheels on the first named 50 shaft; substantially as described.

4. In a street cleaning machine, the combination of a wagon body, wheels and axles thereto on which the body is mounted, the 55 wheels on the rear axle constituting the driving wheels of the machine, an engine mounted on the wagon body, a connection between the engine and the driving wheels and means to throw such connection into and out of operative relation with the driving wheels, a rotatable shaft, gear and sprocket wheels on 60 such shaft, a connection between such shaft and the engine, and means to throw such connection into and out of operative relation with the shaft, rotatable brushes, journal 65 bearings for such brushes, gear wheels on the

rotatable brushes arranged to engage with the gear wheels on the shaft, an apron, a runway from the rear end of the apron, an elevator in the runway, such elevator extending over the sprocket wheels on the shaft, rotatable shafts mounted in journal bearings on the wagon body, and chains attached to the journal bearings of the brushes and of the rotatable shaft and to the shafts on the wagon body, respectively, means to rotate the shafts 75 on the wagon body, and means to attach a wagon to the machine; substantially as described.

5. In a street cleaning machine, the combination of a wagon body, wheels, axles on 80 which the body is mounted, the wheels on the rear axle secured thereto to turn therewith, an engine mounted on the wagon body, a connection between the engine and the rear axle, means to throw such connection into 85 and out of operative relation with such engine and axle, an additional shaft, gear and sprocket wheels on such additional shaft, a connection between the axle and the additional shaft, means to throw such connection 90 into and out of operative relation with such axle and shaft, rotatable brushes, journal bearings for such brushes, gear wheels on the rotatable brushes arranged to engage with the gear wheels on the additional shaft, an 95 apron, a runway extending from the rear end of the apron upwards and backwards, an elevator in such runway, such elevator extending over the sprocket wheels on the additional shaft, chains attached to the respective journal bearings, rotatable shafts mounted on the wagon body, a connection between the chains and the shafts, and means to rotate the shafts; substantially as described.

6. In a street cleaning machine, the combination of a wagon body, an engine provided with a clutch mounted thereon, a rotatable shaft forming the axle of the driving wheels of the machine, driving wheels, a connection between the engine and the shaft, an 105 additional shaft, gear and sprocket wheels on such additional shaft, a connection between such first named shaft and the additional shaft, means to throw such connection into 110 and out of operative relation with the shafts, rotatable brushes, journal bearings for such brushes, gear wheels on the rotatable brushes arranged to engage with the gear wheels on the additional shaft, an apron, a runway extending from the rear end of the apron upwards and backwards, an elevator in such runway, such elevator extending over the sprocket wheels on the additional shaft, and means to raise the brushes, the apron, and the runway above the street and to an inoperative position; substantially as described.

FELIX ROGOWSKI.

In the presence of—

J. S. DERENSKI,

CHARLES TURNER BROWN.
